UNITED STATES PATENT OFFICE.

WILLIAM C. HECKEROTH, OF ERIE, PENNSYLVANIA, ASSIGNOR TO ERIE CITY IRON WORKS, OF ERIE, PENNSYLVANIA, A CORPORATION OF PENNSYLVANIA.

FUEL-FEEDING DEVICE.

Application filed January 16, 1922. Serial No. 529,521.

In burning pulverized fuel where the fuel is carried in with the major portion or all the air for combustion there has been difficulty in distributing the heat of the furnace so as to prevent injury to the walls and to deliver the most intense heat at the desired part of the furnace and also in carrying the combustion to as near completion as desired. The present invention is directed to obviating these difficulties.

The invention is illustrated in the accompanying drawings as follows:

Fig. 1 shows a central section of the furnace with the boiler in place thereon.

Fig. 2 a side elevation, partly in section, of a pulverizer.

Fig. 3 a section of one of the discharge pipes.

1 marks the boiler, 2 the furnace, 3 the bridge wall, 4 the rear chamber, 5 the front chamber, the boiler flues from the boiler carrying the products of combustion from the chamber 4 to the chamber 5 and discharge stack 6. Fuel with the air for combustion is delivered through a horizontal discharge nozzle 7 leading from a branch pipe 8. This pipe extends into the furnace horizontally. The discharge nozzle 9 leads from a branch pipe 10 and discharges at an angle to the nozzle 7 intercepting the fuel discharged from the nozzle 7 so as to fan out the incoming fuel with a preponderance of movement upwardly into contact with the boiler.

Supplemental air may be delivered through the openings 11 if desired. Spiral deflectors 12 are arranged in the nozzles 7 and 9 and give to the incoming mixture

of air and fuel a spiral movement at the point of discharge.

The branch pipes 8 and 10 lead from the main pipe 13. The main pipe 13 leads from the pulverizer 14. Any desired type of pulverizer may be used. As shown the pulverizer has the inlet opening 15 leading to the breaker chamber 16. The breaker bars 17 mounted on the shaft 18 are rotated in the chamber 16 and the material broken passes from the chamber 16 into the path of fan blades 19 carrying the material to a restricted annular beater space 20 formed by rotating the cylinder 21 with the beaters 21a mounted thereon and operating on an attrition surface 22. The material is discharged through the passage 23 to a low pressure fan 24 delivering coal and air through the discharge 25 to the main pipe 13.

What I claim as new is:

In a fuel feeding device, the combination of a furnace; and means for feeding pulverized fuel and the major portion of air for combustion together to the furnace comprising a single main conduit discharging through two delivery pipes, one delivering upwardly and the other horizontally, the discharge from these pipes intersecting, the velocity of the columns of discharged fuel and air being approximately equal at the point of intersection and fanning out a resultant movement of fuel and air through the impact of the columns.

In testimony whereof I have hereunto set my hand.

WILLIAM C. HECKEROTH.
